UNITED STATES PATENT OFFICE.

EDWARD E. KILBOURN, OF NEW BRUNSWICK, NEW JERSEY.

CIRCULAR-KNITTING MACHINE.

SPECIFICATION forming part of Letters Patent No. 408,111, dated July 30, 1889.

Original application filed June 14, 1887, Serial No. 241,243. Divided and this application filed May 9, 1889. Serial No. 310,078.
(No model.)

To all whom it may concern:

Be it known that I, EDWARD E. KILBOURN, a citizen of the United States, residing at New Brunswick, in the county of Middlesex and 5 State of New Jersey, have invented certain new and useful Improvements in Circular-Knitting Machines; and I do hereby declare the following to be a full, clear, and exact description of the invention, such as will enable 10 others skilled in the art to which it appertains to make and use the same.

This invention has reference to cylinder knitting-machines in which a circular series of needles is employed for circular work, and 15 also for reciprocating work.

The said invention is illustrated in the accompanying drawings, and is fully disclosed in the following specification and claims, the present application being a division of my 20 application No. 241,243, filed June 14, 1887.

The object of this invention is to provide means for supplying the yarn or thread to the needles of such machines during circular work, and also during reciprocating work 25 during the operations of narrowing and widening, and said invention contemplates certain novel features of construction and combination of parts, whereby these results are accomplished, in connection with the devices 30 for operating the needles for circular and reciprocating work.

In the drawings, Figure 1 represents a front view of a machine embodying my invention. Fig. 2 is a rear view of the same. Fig. 2^a is 35 a detailed view of one of the devices for feeding the yarn to the needles. Fig. 3 is a transverse vertical section of the machine through the axis of the needle-cylinder, some parts being represented in elevation. Fig. 4 is a 40 longitudinal vertical section of a portion of the machine to the left of the axis of the knitting-cylinder. Fig. 5 represents the corresponding section of the portion of the machine to the right of said axis. Fig. 5^a is a view of the 45 needles. Fig. 5^b is a partial plan view on a reduced scale, showing a part of the actuating mechanism. Fig. 6 is a central vertical section of the cam-cylinders for operating the needles, showing the cams in elevation. Fig. 7 is a 50 horizontal section of one of said cylinders. Fig. 8 represents a view of the inside of one

of the carriers for the pickers. Fig. 9 is a view in elevation of the outside of the same. Fig. 10 is a vertical transverse section of one of said picker-carriers. Fig. 11 is a similar 55 partial section showing another form of guiding-grooves. Fig. 12 is a detail view of part of the mechanism.

The machine herein shown is generally used for knitting seamless stockings by first knitting the leg by a continuous circular movement operating all of the needles of the knitting-cylinder. The heel is then formed by a gang of needles used for reciprocating work, which are operated by the reciprocation of 60 the proper operating mechanism during reciprocating work, a certain portion of the needles at each side of the gang being successively thrown out of operation to effect the narrowing of the web, which is then widened by throwing the said needles successively into operation in a reverse order. The foot of the stocking is then formed by a continuous circular movement of the operating device by operating all of the needles, and 65 the stocking is finished by forming the toe in the same manner as the heel. While this is the most general mode of proceeding in using the machine, it may also be used by commencing the stocking at the toe and reversing the 70 order of operation herein described.

The needles preferably used in the machine are latch-needles having pivoted latches of the usual construction, and the shank of each is secured to or formed integrally with a 85 projection or nib upon which the operating-cam acts for the purpose of moving the needles. The needles are arranged in a circular series and are fitted to slide up and down in grooves in the knitting-cylinder A 90 and its nosing A'. The needles are operated by means of two cams, which, as shown in section at B B', Fig. 3, and in detail in Fig. 6, are arranged one above the other and secured to cam-cylinders B² B³, which are concentric with the series of needles and are fitted to turn around the knitting-cylinder A. The lower cam-cylinder is supported by a ring bearing or support b, and the upper cam-cylinder B² is supported upon the lower. 95 The lower cam-cylinder B³ is held in place by means of studs b^x, secured to the ring-bear-

ing, which studs enter in a dovetailed groove b' of the cam-cylinder. The upper cam-cylinder is held in place by means of screws b^* , whose heads enter in a groove b^2 of the upper cam-cylinder. The upper cam-cylinder B^2 is employed to operate a gang of needles which are put bodily out of operation when the heel and toe of a stocking are knit, the lower cam-cylinder B^3 being employed, preferably, in operating the gang of needles which are employed in combination with a reciprocating thread-guide to knit the heel and toe of the stocking.

In order to adapt the needle to the positions of the cams, those needles which are to be operated by the upper cam B have their nibs arranged at the required distance from their heads to be operated by that cam for circular work, and those needles which are to be operated by the cam B' during widening and narrowing—namely, the fashioning-needles—have their nibs arranged at the required distance from their heads to be operated by that cam for both circular work and reciprocating work.

When the entire series of needles is operated for knitting straight circular work—such as the leg of the stocking—both cam-cylinders B^2 B^3 are caused to revolve continuously and simultaneously, so that each needle of the entire circular series is caused successively to move lengthwise to and fro, as required, to take the yarn for the loop formed by it and to cast off the preceding loop or stitch. For this purpose the two cam-cylinders are connected by gearing with, and given a continuous rotary motion by, the main driving-shaft D . The connection between the lower cam-cylinder D^3 and the main driving-shaft is by means of a main wheel e , secured to the lower cam-cylinder, the intermediate wheel e' , fitted to turn on a stud e^2 , the pinion e^3 , secured to the upper end of an upright shaft e^4 , the beveled pinion e^5 , secured to the lower end of the shaft e^4 , the beveled wheel e^6 , gearing into the beveled pinion e^5 , the beveled pinion e^7 , connected to the beveled pinion e^6 and fitted to turn upon a shaft e^8 , and a beveled wheel e^9 , which is secured to the main driving-shaft D and revolves with it. When, therefore, the driving-shaft is caused to revolve in the direction indicated by the arrow, Fig. 1, the lower cam-cylinder is caused to revolve continuously in the direction indicated by the arrow in said figure.

The upper cam-cylinder B^2 is preferably caused to revolve by being connected with the lower cam-cylinder B^3 , and the most convenient method of connecting the two cam-cylinders is by means of a lug c' , secured to the cam-cylinder B^3 and revolving with it, and a pivoted latch or lug c^2 , secured to the cam-cylinder B^2 and adapted to be engaged by the lug c' . When the cylinder B^3 is revolved in the direction indicated by the arrow in Fig. 1, the lug c' will engage the latch c^2 and the

two cam-cylinders will revolve together. The cam-cylinders can be turned by hand independently of each other, and if the cam-cylinder B^3 be rotated backward the lug c' will pass under and raise the latch c^2 , allowing the cam-cylinder B^2 to remain stationary.

I provide a thread-guide E to feed the thread to the entire series of needles when knitting circular work. This thread-guide is mounted upon and carried by the cylinder B^2 and delivers the yarn to the needles in succession before the cam-cylinders operate upon their nibs to depress them. In order that this circular thread-guide E may be readily moved out of its operative position when the heel and toe of a stocking are to be knit, it is secured to a rocking stock f , (see Figs. 2 and 2^a,) pivotally mounted in standards f' , which are attached to the cam-cylinder B^2 , and I provide a locking device for holding said thread-guide securely in either its operative or the non-operative position. This locking device consists of a spring-latch f^2 , provided with a nib to engage an arm f^3 , which projects from the stock of the thread-guide, as best seen in Fig. 2^a. When the circular thread-guide is out of its operative position, the spring-latch engages with the upper side of said arm f^3 , as shown, and when the circular thread-guide is in its operative position said latch engages the under side of said arm.

In order that the latches of the needles may be kept from accidentally flying up when knitting circular work and that they may be positively thrown down, I provide the latch-guard f^4 , which is attached to the stock f of the thread-guide E , and therefore may be readily turned into and out of its operative position with the said thread-guide.

In order to hold the upper cam-cylinder B^2 out of operation when reciprocating work is being done, I provide a locking device for such cylinder, which consists, preferably, of a notched latch F , which engages a lug a' on the cam-cylinder B^2 , as more particularly described and shown in my application, No. 241,243, filed June 14, 1887.

During the reciprocating work I prefer to cause the cam-cylinder B^3 to reciprocate by a portion of the same gearing which is employed for revolving it during circular work, and to employ supplementary gearing to complete the movement. I prefer in this connection to use a supplementary driving-shaft D' for reciprocating work, and to connect so much of the gearing as is then used with said supplementary driving-shaft. The portion of the main gearing previously described, which is used in the said machine for reciprocating work, consists of the main wheel e , the intermediate wheel e' , pinion e^3 , the upright shaft e^4 , the beveled pinion e^5 , and the beveled wheel e^6 . The other portion of the main gearing, which remains connected with the main driving-shaft, consists of the two wheels e^7 and e^9 . In order that the former portion of the gearing may be reciprocated for reciprocating work,

the beveled wheel e^6 is not made fast to the beveled wheel e^7 , and the connection of the said beveled wheel e^6 with the beveled wheel e^7 for circular work consists of disconnectible drivers comprising, preferably, two lugs $h\,h'$, one of which is secured to the back of the beveled wheel e^6 , while the other lug is connected with the beveled wheel e^7 , which is driven by the driving-shaft D. This mode of connection permits the wheel e^6 to be rotated to and fro without affecting the driving-shaft D. A further extent of reciprocation may be obtained, if desired, by the means shown and described for this purpose in my application No. 241,243.

The supplementary driving-shaft is connected with the beveled wheel e^6 through the intervention of a reciprocating rack H and a pinion e^{10} , which is driven by said rack and is connected with the beveled wheel e^6 . The stock of the reciprocating rack H is fitted to slide in bearings connected with the main frame, and it is connected by a connecting-rod H' with a crank H², which is secured to the shaft H³, and this crank-shaft is connected with the supplementary driving-shaft by means of beveled wheels e^{11} and e^{12} . In order that the said reciprocating mechanism may be connected with and disconnected from the cam-cylinder B³, the connection is made through the intervention of a clutch member I, Fig. 13, whose hub is fitted to slide upon pinion-shaft b^8 , and is connected with it by a spline or feather of the usual construction. The clutch member I has a tooth i, which is adapted to engage a notch formed in the hub i' of the wheel e^6 and the portion of the main gearing connecting it with the cam-cylinder B³, and the said cam-cylinders are caused to reciprocate by the continuous revolution of the driving-shaft D'. This clutch member I may be moved by means of a shipper, one arm of which J is forked and engages a groove of the clutch member I, and the other J' has the form of a handle, the two parts being connected by a vertical shaft suitably mounted on the main frame.

During reciprocating work the yarn is fed to the gang of needles then at work by means of a supplementary thread-guide E', which is caused to move to and fro in a circular curve by a movement derived from that of the cam-cylinder B³, then operating. In order that this supplementary thread-guide E' may be moved out of the way while circular work is being done and may readily be put in position for reciprocating work, it is connected pivotally with a movable bracket-arm E⁷, that is supported by a standard E⁸ at the back of the machine. The hub g³ of the bracket-arm is fitted to turn on the head of the standard, and is provided with a pin g⁴, passed through said hub and arranged to engage with a hole in the collar g⁶ of the bracket-standard E⁸, when the bracket-arm is in the position to hold the pivoted shaft g⁵ of the supplementary thread-guide centrally over the series of needles in the knitting-cylinder. When the

supplementary thread-guide is to be thrown out of operation, this pin is withdrawn and the bracket-arm, with the thread-guide, is swung backward, so as to remove the thread-guide from its operating position, and it may be held when so removed by engaging the pin in a second hole in the collar g⁶. As the supplementary thread-guide is caused to move in alternately reverse directions, a duplex latch-guard f⁵ is combined with it to keep the latches of the needles from accidentally flying up when knitting reciprocating work. The supplementary thread-guide is represented in the drawings in its operating position, and it is then caused to reciprocate by means of a cam E², Figs. 2 and 7, secured to the collar of the lower cam-cylinder B³. The ends of this cam operate alternately upon the shank of the supplementary thread-guide, and in order that the supplementary thread-guide may stand at rest for a short period at each end of its reciprocating movement a spring-driver j, Fig. 4, is introduced between the cam E² and the driving-arm E⁶ of the thread-guide, and stops E⁴ E⁵ are applied to limit the reciprocating movement of the supplementary thread-guide. Thus when one end of the cam is driving the supplementary thread-guide to the right hand the stop E⁵ stops its movement at the proper time, and the spring-driver, yielding to the pressure of the oblique end of the cam, permits the cam to pass it. A corresponding operation takes place when the supplementary thread-guide is moved to the left hand and is stopped by the stop E⁴. In order that the yarn may be subjected to the proper tension, the thread-guide is fitted with a thread-tension of one of the usual constructions, and a spring thread-take-up j', Fig. 4, also is provided to take up and give out slack yarn, as is customary in the use of knitting-machines. One of the usual constructions of thread-tensions which I have used with success is represented at E¹⁰, Figs. 1 and 4, and consists of a pin having a slotted head. The yarn is passed through the slot of the head of the pin, and the pin is turned more or less to make the yarn deviate more or less from a straight line, or to encircle the pin more or less, as may be found necessary to produce the resistance to the free movement of the yarn required to produce the required tension.

The fashioning-needles are raised and lowered out of and into operative position during narrowing and widening by means of pickers K, Figs. 8, 9, 11, and 12—one for each side of the gang of fashioning-needles. Each of these pickers is fitted to slide up and down in a carrier L, which is moved as described to place the picker in position to operate upon the required needle. Each carrier is fitted in grooves k k' in the frame-work of the machine, said grooves being concentric with the series of needles, so that the pickers may operate successively upon the needles in exactly the

same manner. These grooves being concentric with the knitting-cylinder and the carriers being segmental in form, the said carriers will work in the same grooves on opposite sides of the knitting-cylinder. This construction enables me to employ short pickers and construct them of the same size for both sides of the machine. If preferred, the ends of the carriers may be grooved and the grooves 10 k k' may be replaced by circular ribs, as shown at k'' , Fig. 12.

In order that the same picker may be used to move the needle for narrowing out of its working position and to move it for widening 15 into its working position, each picker is provided with two lugs k^2 k^3 , Figs. 8 and 11, one of which k^2 acts beneath the supplementary nib of the needle-shank and pushes the needle out of its working position for narrowing, 20 while the other k^3 acts upon the upper side of said nib and pulls it back into its working position for widening. The pickers are caused to rise and fall by means of a reciprocating cam K' , which is preferably fitted to turn 25 upon the stock of the knitting-cylinder below the knitting-cam, and each picker K is provided with a pin k^4 , which engages the groove of said cam for operating said picker. The picker-cam is provided on its periphery with 30 gear-teeth k^5 , which engage with the teeth of a segment k^6 , which is mounted pivotally upon a stud k^7 , secured to the frame of the machine. To this segment is secured a second segment n , the teeth of which are engaged by those of 35 a rack N , which is supported in guides and has its shank connected by a pin with an upright lever N' , the lower end of which is pivoted to the frame of the machine. The lever N' is formed in the shape of a yoke and has 40 two projections n^2 n^3 within the range of the two members n^4 n^5 of a cam N^2 , which is secured to the crank-shaft H^3 of the machine, which is driven by the supplementary driving-shaft D' . It will be seen that a revolution 45 of the shaft H^3 will cause a reciprocation of the rack M and segments n and k^6 , thereby actuating the cam K' and the pickers K .

The pickers K are given an alternating 50 movement toward or from the center of the gang of fashioning-needles after each carrying or shifting of the picker. Each carrier L is provided with a worm-segment l , which is engaged by a screw l' , secured to a shaft l'' , 55 which is fitted both to rotate and to move endwise in its bearings. Each screw-shaft is fitted with a pinion l^1 , the teeth of which engage with those of a wheel l^1 , which is a driving-wheel common to both of the screw-pinions l^1 , as shown in Fig. 1. This wheel l^1 is caused to turn continuously during reciprocating knitting. The gearing between the screws l' and the supplementary driving-shaft is so proportioned that each screw is 60 caused to revolve one-half of a revolution for each revolution of the crank-shaft H^3 , which imparts reciprocating movement to the thread- 65

guide E' , and the pitch of the screws l' l'' is double the pitch or gage of the needles in the series, so that a half-turn of the screw is sufficient to move the carrier which is controlled and the picker from one needle to the next in the series. 70

The screws are given an endwise movement for the purpose of allowing the carrier a period of rest before each advance by a cam, and I prefer to use two cams for each screw, and to arrange these in the form of cam-collars l^5 , Fig. 3. These cam-collars, one of which is shown in Fig. 3, are located at the 80 opposite sides of the bearing l^6 , in which the screw-shaft revolves, and the screw-shaft is provided with pins l^7 , (one being shown in Fig. 3,) which bear against the collars, so that as these pins move during the turning of the 85 screw along the inclined faces of the cam-collars the screw-shaft l^2 and screw l' are caused to move endwise, as more fully shown in my application No. 241,243.

During the narrowing of the work the carrier is caused to move toward the middle of the gang of the fashioning-needles, and during the widening of the work the carrier is caused to move outward. In order that these movements in reverse directions may be obtained from the driving-shaft while always revolving in the same direction, the screw driving-wheel l^4 , which is fitted to revolve upon a stud secured to the frame of the machine, has secured to its hub a beveled pinion l^8 , Fig. 3, which engages with a beveled wheel l^9 , whose hub l^{10} is fitted to turn upon the stock of the knitting-cylinder A . A corresponding beveled wheel l^{10} , having its teeth opposed to the teeth of wheel l^9 , is also secured to the hub l^{11} , so that the two wheels revolve together. At the side of the hub of these beveled wheels which is opposite to the beveled pinion l^8 a second beveled pinion l^{12} is arranged, and this beveled pinion is connected to the supplementary driving-shaft D' through the intervention of the wheel l^{13} , secured to the hub of the beveled pinion l^{12} , the intermediate wheel l^{14} , secured to an intermediate pinion l^{15} , (shown in dotted lines in Fig. 115 2,) the pinion l^{16} , (also shown in dotted lines, Fig. 2,) secured to the crank-shaft H^3 , and the beveled wheels e^{11} e^{12} , which impart motion from the supplementary driving-shaft B to the crank-shaft H^3 . The diameter of the pinion l^{12} is less than the space between the faces of the reversely-beveled wheel l^9 l^{10} , so that it can operate in connection with one of said beveled wheels without touching the teeth of the other, and the shifting of the driving-pinion from one of said wheels to the other changes the direction of rotation of said wheels, thereby reversing the direction of rotation of the screws l' and the carriers L . 120

In order that the driving-pinion may be 130 shifted automatically from one wheel to the other, the hub of said driving-pinion l^{12} and of the wheel l^{13} , secured to said pinion, is fitted to turn upon a stud l^{17} , which is held by

an arm l^8 , which is pivoted and swings upon the axis of the intermediate wheel l^4 , so that the driving-pinion may be shifted from one of the change-wheels l^9 l^{10} to the other without affecting the engagement of the wheels l^8 and l^{15} . The driving-pinion is also provided with a stud or roller l^9 , Fig. 3, and the hub l^{11} of the change-wheels is provided with a rail l^{20} , secured thereto between said change-wheels. 5 Two segments l^{21} are secured, preferably by means of screws, between the change-wheels, the teeth of said segments corresponding to those of the change-wheels. When the driving-pinion impelling either of the change-wheels causes the appropriate segment to come into gear with the pinion-teeth, said pinion engages said segment and is shifted from one of said change-wheels to the other, and the end of the rail l^{20} is in the proper position to 10 permit the stud or roller l^9 of the driving-pinion to pass around it during this shifting operation, and the said rail serves to hold the said pinion in engagement with one or the other of said change-wheels by means of the 15 stud l^9 . The extents of the portions of the change-wheels which are between the segments and which are engaged by the driving-pinion before shifting determine the number of turns imparted to the carrier-screw, the 20 number of times the carriers are moved, and the number of needles that are moved into and out of operation in narrowing and widening the work.

When the machine is narrowing or widening, it is desirable that the thread-guide E' , which is then reciprocated, should have its extent of motion varied to correspond with the less or greater extent of the narrowed or widened work. In order that this variation 35 may be properly effected, the picker-carriers L are provided with the stops E^4 E^5 , which are moved with them, said stops being connected with the carriers preferably by means of the brackets E^9 E^{10} ; hence whenever a picker-carrier is moved the corresponding stop is moved, and the extent to which the reciprocating thread-guide can be moved by its cam varied. The practical effect of limiting the movement of the reciprocating thread-guide 40 by stops and permitting the needle-cam B' , which is then reciprocated, to be moved past the thread-guide in the continued movement of its cam-cylinder B^3 , is to transfer the reciprocating thread-guide from one side to the 45 other of the reciprocating cam, so that the thread-guide is always in advance of that cam in whichever direction the cam may be moved. This transfer is important, and may be effected by providing stops E^4 E^5 upon some 50 rigid portion of the frame if it is not desired to have said stops advanced by the picker-carrier. This transfer obviates the necessity of using switch-cams, which tend to break the needles, and which also permit a certain 55 amount of freedom of movement of the needles, which is objectionable.

The needle-cams, actuating mechanism,

and stop devices form the subject-matter of my application, No. 241,243, filed June 14, 1887; the hook-partitions the subject of my 70 application No. 310,077, filed May 9, 1889, and the narrowing and widening mechanism the subject of my application No. 310,079, filed May 9, 1889, and are not claimed herein.

What I claim, and desire to secure by Letters Patent, is—

1. The combination, substantially as before set forth, of the knitting-cylinder, two cam-cylinders for operating the needles thereof for circular work, the thread-guide for circular work, and a locking device for holding 80 said thread-guide out of its operative position.

2. The combination, substantially as before set forth, of the knitting-cylinder, the two cam-cylinders for operating the needles thereof 85 for circular work, the thread-guide for circular work, and a reciprocating thread-guide, which is reciprocated in combination with one of said cam-cylinders for reciprocating work.

3. The combination, substantially as before set forth, of the reciprocating thread-guide, the stop therefor, and the picker-carrier.

4. The combination, substantially as before set forth, of the needle-cylinder, the needles, 95 the cam by which the needles are operated for reciprocating work, the picker, the picker-carrier, the thread-guide which is operated for reciprocating work, and means for transferring said thread-guide from one side of 100 said cam to the other side thereof, including a stop for said thread-guide moving in a determined relation with the picker-carrier.

5. The combination, substantially as before set forth, of a needle-cylinder, the needles, 105 the cam by which the needles are operated for reciprocating work, the pickers, the picker-carriers, the thread-guide which is operated for reciprocating work, and means for transferring said thread-guide from one side 110 of said cam to the other thereof, including stops mounted on and moving with said picker-carriers.

6. The combination, substantially as before set forth, of a knitting-cylinder, the needles, 115 two cam-cylinders, one of which is in operation only during circular work, means for imparting motion to one cam-cylinder for reciprocating work, thread-supplying devices, and means for operating said thread-supplying 120 devices for circular and reciprocating work.

7. The combination, substantially as before set forth, of the knitting-cylinder, the needles, a cam-cylinder which only works during circular work, a reciprocating cam-cylinder, 125 thread-supplying devices for circular work, a separate thread-guide for reciprocating work, and means for operating the latter thread-guide in connection with the reciprocating cam-cylinder.

8. The combination, substantially as before set forth, of a knitting-cylinder and its needles, two cam-cylinders, one of which only works during circular work, and thread-

supplying devices, the thread-supplying devices for reciprocating work moving in engagement with the reciprocating cam-cylinder.

- 5 9. The combination, substantially as before set forth, of a needle-cylinder and its needles, two cam-cylinders, one of which only works during circular work, and thread-supplying devices, the thread-supplying device for re-

ciprocating work moving in unison with the reciprocating cam through the whole or a part of its movement.

In testimony whereof I affix my signature in presence of two witnesses.

EDWARD E. KILBOURN.
